UNITED STATES PATENT OFFICE.

JOHN S. VENSON, OF FOUR MILE, NEW YORK.

VENT FOR STEAM-PIPES.

SPECIFICATION forming part of Letters Patent No. 310,338, dated January 6, 1885.

Application filed July 3, 1884. (No model.)

To all whom it may concern:

Be it known that I, JOHN S. VENSON, a citizen of the United States of America, residing at Four Mile, in the county of Cattaraugus and State of New York, have invented certain new and useful Improvements in Vents for Steam-Pipes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to certain new and useful improvements in vents for steam-pipes, the object of my invention being to provide a means for allowing the condensation of steam to escape automatically from the feed-pipe; and to this end my invention consists in the construction and combination of parts herein-after fully described.

In the accompanying drawings, Figure 1 is a side view. Fig. 2 is a section, and Figs. 3 and 4 are detail views.

A represents a casting, preferably made of a single piece, and provided at one end on its exterior with a screw-threaded portion, *a*, by means of which it may be secured at a suitable point in the steam-conducting pipe *B*, which leads from the boiler, and is provided with a branch pipe which leads to the steam engine. The casting *A*, near the screw-threaded end *a*, is provided with a valve-seat, *a'*, which is formed at the end of the passage *C*, which is directly connected to a discharge opening or passage, *C'*, the terminal portion of which passage is screw-threaded for the reception of a discharge-pipe through which the condensed moisture is conveyed. The portion *D* of the casting *A* is provided with an opening or passage-way, *D'*, which is connected to the passages *CC'* by a smaller opening, *d*. The interior of the opening *d* is screw-threaded for the reception of a set-screw, *E*, which is locked in position by a nut, *e*, which passes over said set-screw and abuts against the end of the portion *D* of the casting, as shown, and prevents movement of said set-screw when forced upon the same. The set-screw *E*, as shown in Figs. 2 and 4, is provided with a recessed end, which

recess consists of a circular cut-away portion, *f*, having an opening, *f'*, which extends to the base of the same. A valve, *F*, having a reduced end portion, *F'*, with projecting flanges *g*, adapted to be placed so that its head or end will rest upon the valve-seat *a'*, is inserted in the end of the casting, as shown, and is retained in position within the opening *C* by means of a spiral spring, *H*, which is provided at one end with a hooked end which passes through an opening, *g'*, in the end of the valve *F*, while the opposite end of said spring is secured within the recess in the end of the set-screw *E*, the straight portion *h* of said spiral spring passing through the opening *d* in the casting. The end of the spiral spring is provided with a suitable head, which lies within the opening *f* within the set-screw, while the portion of the spring adjacent to the head will pass through the recess *f'*. The spring *H*, which is connected, respectively, to the set-screw and valve, will exert an outward pressure upon the valve *F*, and said pressure can be regulated by adjusting the set-screw.

The operation of my invention when applied to a steam-pipe is as follows: When steam is admitted to the pipe *B*, to which the connecting-pipe to the steam-engine is attached, the pressure within said pipe will force the valve *F* snugly upon its seat, and when the pressure or steam is cut off from said pipe the condensed steam or water will collect in the lower portion of said pipe, to which my improved vent is attached, and the valve will be thrown from its seat by the spiral spring and allow the water to escape through the discharge-pipe.

By the means hereinbefore described I am enabled to provide an automatic vent which is effective in operation and simple in construction, and which will always be open when there is no pressure within the supply-pipe, and which may be adjusted so as to open at different pressures, and which will also afford a means for admitting air to the steam-pipe, and thus preventing a vacuum therein.

I am aware that previous to my invention it has been proposed to arrange metallic strips in a steam-trap, which act thermostatically to force by their expansion a valve to close the discharge-opening, and by their consequent

contraction to remove the valve from said opening; but such device as contrasted with my improvement is uncertain in its operation, in that the heating or cooling of the metallic strip has to be relied upon to secure the necessary movements of the valve. In my improvement the quick and positive effect of the steam-pressure is the actual medium.

I claim—

- 10 1. The improved attachment herein described, consisting of a vent device having a portion for connection to the steam-supply circuit, and a discharge-opening, in combination with a valve interposed between said connecting portion and discharge, and adapted to be closed by pressure in the supply-circuit, and automatically open when said pressure is removed, substantially as set forth.
- 15 2. The improved attachment herein de-

scribed, having a portion for connection to the steam-supply circuit, and a discharge-opening, in combination with a valve interposed between said connecting portion and discharge, to operate as described, and means for adjusting said valve, substantially as described.

25

3. The improved vent for steam-pipes, consisting of the casting A, provided with a discharge-opening, a passage-way to one end of the same, and a valve located in one end of the opening, and provided with a spiral spring 30 which is attached to an adjusting means, substantially as shown, for the purpose set forth.

In testimony whereof I affix my signature in presence of two witnesses.

JOHN S. VENSON.
